(57) **CLAIM**

We claim the ornamental design for the bollard sleeve cover, as shown and described.

DESCRIPTION

FIG. 1 shows an isometric view of the entire bollard sleeve cover poised for receipt over a post, where the post is shown in phantom for illustrative purposes only and form no part of the claimed design;

FIG. 2 is a view similar to that of FIG. 1, where the bollard sleeve cover is partially received over the post;

FIG. 3 is an enlarged view of the bollard sleeve cover showing the cap exploded from an end of the bollard sleeve cover;

FIG. 4 is a top view of the assembly of FIGS. 1 and 2 showing the cap positioned in place on top of the bollard sleeve cover;

FIG. 5 is a view looking through the open end of the bollard sleeve cover with the cap in place at the opposite end;

FIG. 6 is a front view showing one end of the bollard sleeve cover;

FIG. 7 shows a rear view of the bollard sleeve cover opposite to that shown in FIG. 6;

FIG. 8 shows one side view of the bollard sleeve cover; and, FIG. 9 shows the opposite side view of the bollard sleeve cover.
